EXTENSION DEVICE

August F. Kraemer, Providence, R. I., assignor to
 Louis Stern Company, a corporation of Rhode
 Island

Application November 6, 1931, Serial No. 573,320

8 Claims. (Cl. 24—71)

This invention relates to an extension device of the type to be positioned intermediate the ends of a bracelet, and has for one of its objects the provision of a construction which will permit of 5 an enlargement of the bracelet by unfolding, and which will also permit of a resilient extension that the bracelet may contract and hold the watch or bracelet snugly about the wrist.

Another object of this invention is the provision of a construction in which the elastic extension will be smooth in its action in both expanding and contracting.

A further object of this invention is the provision of a construction in which the sections will closely nest one within the other to avoid a bulky device.

A still further object of this invention is the provision of a construction in which the end portions of the sections will conform to the appearance of the bracelet to cause the extension device to have a shorter and less bulky effect upon the observer.

With these and other objects in view, the invention consists of certain novel features of construction, as will be more fully described, and particularly pointed out in the appended claims.

In the accompanying drawing:

Fig. 1 is a top plan view of a section of a chain with my extension device secured therein.

Fig. 2 is a side elevation of the structure shown in Fig. 1.

Fig. 3 is a central sectional view of the extension and an end link attached to each end of the device with the parts in central section.

Fig. 4 is a perspective view of the box section and the slide member thereof, with the box section broken away to show the construction of the interior thereof.

Fig. 5 is a central sectional view through the box section.

Fig. 6 is a sectional view on line 6—6 of Fig. 2.

Fig. 7 is a sectional view on line 7—7 of Fig. 2.

Fig. 8 is a sectional view on line 8—8 of Fig. 3.

It has been found desirable in the use of watch bracelets to provide an extension device to permit the bracelet and watch attached thereto to be removed over the hand of the wearer without detachment of any of the parts, and it has been customary to use for such purpose, a folding extension device inserted intermediate the ends of the bracelet. It is also desirable in the use of watch bracelets to provide an elastic action that the bracelet may snugly grip the wrist to maintain the watch and its bracelet in the desired position along the arm which was accomplished at one time by providing link units which had elastically extendible parts. However, in the provision of elastically extendible units, the spring which permits of resilient extension necessitates a link of closed construction.

With the advent of links having open centers that a cooler bracelet and one which would not cause heating of the wrist, the elastic link was no longer usable, and in order that the resilient action may be attained in a bracelet using open center links, I have provided the resilient action in one of the sections of an extension device, and in order that the device, which of necessity, is of sufficient thickness to contain the spring may be housed with lesser bulk of the entire device, I have cut out the intermediate section to receive both of these sections between its side walls for compact resting of the parts, and in order that the device may conform to the appearance of the chain in which it is attached, I have cut out openings in the channel sections and embellished the edges of the top wall which remain, in the same manner as the links of the chain ornamented and as the box section with its resilient slide does not extend the full length of the channel section I have formulated a link at the end of the slide generally in the shape of one of the links of the chain with an opening therein to register with an opening in the top wall of the channel section which gives a chain effect to the end of the device and cause the same to be less prominent so as not to detract from the chain and thus present less bulk in appearance; and the following is a detailed description of the present embodiment of this invention illustrating the preferred means by which these advantageous results may be accomplished.

With reference to the drawing, 10 designates the channel section which is provided with a portion of a top wall 11 and side walls 12. The end of the top wall is rolled to provide an eye 13 to hingedly receive the end link 14 of a chain. The opposite end section is designated 15 and is generally box shape having a top wall 16, side walls 17 and a bottom wall 18. Within the narrow box section 15 there is provided a narrow portion for a slide member 19 having an abutment end 20 between which abutment end and the box end wall 21 a spring 22 extends to move the slide member into the box 15.

The slide is concave as indicated at 23 to conform to the helical spring 22 which rests thereagainst. It is found that by concaving the slide in this manner that the spring is guided in its action and a much freer longitudinal movement of this slide with reference to the box is afforded than where the slide is a flat construction. The free end of the slide is formed in the shape of a link 24 at least twice the width of the narrow portion having an opening 25 which link is considerably wider than the concave portion of the member located in the box, and an eye 26 rolled on the end of this slide member for attachment to the end link 27 of the chain.

The two sections 10 and 15 are joined together

by an intermediate section 27 which is U-shaped having the bridge portion 28 of the U hingedly received in the eye 29 rolled from the top wall 16 of the end section 15, while the arms 30 of this section are provided at their ends with laterally extending projections 31 to pass through openings 32 in the side walls 12 of the channel section to be headed or riveted over as at 33 and pivotally mount this end of the section in position. Openings 34 are provided in the top wall of the channel section and the end opening 35 registers with the opening 25 in the slide member when the device is in folded position to give the effect of one of the open links of the chain in which the extension device is attached.

In order that the sections may be held in folded position I have provided detents 36 on both sides of the box section to snap into recesses 40 in the inner edges of the bars or arms 30 of the intermediate section and adjacent one end thereof as shown in Figures 3 and 6, and I have provided protuberances or detents 37 on the channel walls 12 to snap over and beyond the outer edges of the bars or arms of the intermediate section adjacent its opposite end to retain the sections in folded position.

By this construction it will be observed that I provided a foldable extension device which is also elastically extendible when in folded position and which may be secured intermediate the ends of an open frame link chain and one which conforms to the appearance of the chain to harmonize with the effect thereof.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In an extension device a pair of sections hinged together, a slide member mounted in one of the sections, and resilient means to move said member into contracted relation with reference to the section in which it is mounted, said slide member being curved laterally throughout its width, said resilient means also being curved laterally so as to conform with the curvature of the slide member.

2. In an extension device a pair of sections hinged together, a slide member mounted in one of said sections, and a round helical spring to move said member into the section in which it is mounted, said member being concaved throughout its width to fit and lie along said spring to assist in providing an even expanding and contracting movement of the parts.

3. In an extension device, a box shape section, a slide member therein, yielding means to move said member into its section, a channel section and an intermediate section hinged at its ends to said box and channel sections for folding of the sections one on the other, said intermediate section consisting of a pair of spaced bars to receive said box section and said channel section being of a size to receive both of said sections between the walls thereof, and means to snap over the edges of said intermediate section to retain said sections in folded position.

4. In an extension device, a box shape section, a slide member therein, yielding means to move

said member into said section, a channel section and an intermediate section hinged at its ends to said box and channel sections for folding of sections one on the other, said intermediate section consisting of a pair of spaced bars to receive said box section and said channel section being of a size to receive both of said sections between the walls thereof, and means on said channel section and said slide member for attaching said device in a chain, and means to snap over the edges of said intermediate section to retain said sections in folded position.

5. In an extension device, a box shape section, a slide member therein, a helical spring to move said member into said section, said member being 15 arc shape to conform to the shape of the spring, a channel section and an intermediate section hinged at its ends to said box and channel sections for folding of the sections one on the other, said intermediate sections consisting of a pair of 20 spaced bars to receive said box section and said channel section being of a size to receive both of said sections between the walls thereof.

6. In an extension device, a box shape section, a slide member therein, yielding means to move 25 said member into said section, a channel section and an intermediate section hinged at its ends to said box and channel sections for folding the sections one on the other, said intermediate section consisting of a pair of spaced bars to receive said 30 box section and said channel section being of a size to receive both of said sections between the walls thereof, detent means on said box and channel sections to snap over the inner and outer edges of the bars of said intermediate section adjacent 35 its opposite ends to hold the sections in folded position.

7. In an extension device, a relatively narrow section, a slide member having a relatively narrow portion mounted in said section, and resilient 40 means to move said slide member into contracted relation with reference to the section in which it is mounted, said slide member being provided with a unitary integral enlarged portion at its outer end at least twice the size of said narrow portion and provided with an opening to conform 45 to the shape of the links of a bracelet, and a channel section secured to said section in hinged relation thereto and housing said section when in folded position and having an opening to align 50 with the opening in said slide member when in contracted position.

8. In an extension device, a pair of sections hinged together to swing to an end to end relation, one of said sections being relatively narrow, 55 a slide member having a relatively narrow portion mounted in the relatively narrow section, resilient means to move said slide member into contracted relation with reference to the section in which it is mounted, said slide member being provided with a unitary integral enlarged portion at its outer end portion at least twice the size of 60 said narrow portion and provided with an opening to conform to the shape of the links of a bracelet, and means additional to said enlarged end portion and extending beyond the end thereof to connect one end of said device in a bracelet with said sections in said end to end relation, means to connect the other end in a bracelet, and 65 means to hold said sections in folded position one over the other.

AUGUST F. KRAEMER.
